RADIO CONTROL HEAD

Bertram A. Schwarz, Kokomo, Ind., assignor to
 Zenith Radio Corporation, Chicago, Ill., a corporation of Illinois

Application January 8, 1937, Serial No. 119,551

6 Claims. (Cl. 250—20)

This invention relates to a remote control and more specifically to a remote control head for radio receiving sets.

With the widespread use of radio receiving sets at present it is often necessary to place the receiver chassis including the tubes and operating apparatus at one point and to locate at some point removed therefrom means for tuning and turning off and on the apparatus. This is particularly true in automotive sets where it is usually necessary to mount the chassis and working parts on the dash or fire wall between the engine and the interior of the car and to mount the control knobs and dial included in a control head either on the instrument panel or upon the steering column so that they will be at a point readily accessible to the operator.

It is therefore the object of my invention to provide a control head which may be conveniently attached and which includes all the necessary manual operating functions of a radio receiver set.

It is a further object of my invention to provide such a control head as may be adapted to be mounted at different locations and under different circumstances.

With these and other objects in view the embodiments of my invention are described in the following specification and claims and illustrated in the accompanying drawings, in which:

Figure 1 is a top plan view of my invention as applied to a steering column device.

Figure 2 is an enlarged sectional view taken on line 2—2 of Figure 1.

Figure 3 is a sectional view taken on line 3—3 of Figure 2.

Figures 4 and 5 are sectional views taken substantially on lines 4—4 and 5—5 respectively of Figure 3.

Figures 6 and 7 are diagrammatic views of my invention applied to a different plate for supporting the control.

The particular type of assembly mainly disclosed in the present invention is that adapted to be applied to a steering column but the working portions of the apparatus may readily be applied to a flat plate which is insertible in the instrument panel as well.

Referring now specifically to Figure 1, the casing 2 is divided into three portions: a front plate 4; rear plate 6; and an end one half round portion 8 which is adapted to be secured against the other half of the casing by suitable screws 10, the steering column passing through the aperture between the two portions.

The opposite end of the casing is enlarged to form a bulbous aperture therein within which portion of the apparatus the necessary control means are located. This bulbous aperture supports therein a visible tuning dial 5 and two control knobs 9 and 7, one of which tunes the set and rotates the dial, the other being a volume and tone control, all of which will be more clearly set forth in detail as the specification proceeds.

A pear shaped bracket 12 is supported within the bulbous cavity of the control head and centrally located in the larger end is a raised circular portion 14, the end of which is open and supports an insulated annular ring 16 within the center of which is supported a socket 18 having therein an electric lamp 20. A suitable cable 22 supplies the socket from some remote source with electrical energy. The other portion of the pear shaped member 12 extends toward the edge of the bulbous opening and includes a rearwardly extended tubular portion 24 which carries therein a bushing 26 the exterior portion of the extension 24 being screw-threaded and having applied thereon a cap 28 which clamps a portion of a flexible hollow cable 30 to the housing. Within the cable is a rotatable flexible drive shaft which terminates with a tongue connector 32 which fits within a slot within a connector 34 rotatable within the bushing 26, said member 34 being of reduced diameter as it approaches the front of the casing and having a second tongue terminal 36 which fits within a slot in the inner end of a shaft 38 which extends forwardly and outside of the casing.

Concentric with and surrounding the shaft 38 is a hollow sleeve 40 which is rotatable within a threaded bushing 42, the latter being in engagement with a threaded opening 44 in the forward portion of the bracket 12. The bracket 12 at this point extends through an opening 46 in the outer shell and is clamped thereto by a suitable nut 48 applied to the threaded portion extending through the forward face.

To the opposite side of the bracket 12 is connected a supporting bracket 50 by screws 52, said connection in the plate having a slot so that it may be moved readily around the central portion of the device for adjustment. Through this plate extends an opening 53 through which extends a sleeve 54, a portion extending through the opening being externally threaded and a nut 56 tightened down upon the plate to clamp it against the shoulder on the other side to rigidly secure the sleeve to the plate. This sleeve also extends forwardly through an aperture in the

outer casing and is externally threaded on the projecting portion. A clamping nut 58 is threaded thereon to clamp the sleeve to the outer casing. In this manner both the sleeve and the bracket 12 are clamped to the outer casing.

Within the sleeve 54 is a hollow rotatable sleeve 60 which extends out through the forward end of the sleeve 54, is externally screw-threaded and has rigidly secured to rotate therewith a knob 10 or collar portion 62 which is held in place by a nut 64. The inner end of the sleeve 60 is enlarged and the outer periphery has suitable knurls cut therein as shown at 66 which knurls are made available through an opening 67 in the outer sleeve 54 to contact with gear 68 which is pivoted on a suitable shaft support 70, said shaft support being the operating member of a tone control element 72 also supported on the plate 50. Thus when the knob 62 is turned it rotates the sleeve 60 and drives the tone control element through 66 and 68.

Within the sleeve 60 is supported a rotatable shaft 74 which has secured on the outer end an operating knob 7, the inner end of said shaft being connected by a tongue and groove joint 78 to a rotatable flexible shaft 80 within a flexible housing 82, said flexible housing 82 being clamped to the end of the outer sleeve 54 by a cap 84.

In the central portion of the outer casing is an opening within which is secured a circular annular bezel 86 which extends inwardly and has tongues 88 thereon adapted to be clamped over the periphery of the bracket 12 at certain points. Within this bezel is secured an annular shield 90, most of the surface of which is covered with opaque paint 91 but certain portions thereof are left translucent to form the dial numerals. Clamped under the edge of the bezel and across the face of the whole is a transparent cover 92.

Also clamped between the end of the annular member 90 and the edge of the bracket 12 is a spider 94 carrying at its center a bushing 96 through which extends a rotatable stub shaft 98 carrying at its outer end a dial arrow 100, said dial being riveted to the end of the shaft by a rivet 102 and rotating with the shaft, said arrow dial also completely filling the circular opening in the annular member 90. Secured to the other end of the stub shaft 98 is a transparent gear 104 which is adapted to mesh with a transfer gear 106 carried on the bracket 12 by a suitable support, said transfer gear meshing with a gear 108 carried upon the stub shaft 34 and rotatable therewith so that when the shaft 34 is rotated the dial arrow will also be rotated to indicate the position of the tuning elements on a remote set.

The sleeve 40 has adjacent its inner end two collars 110 integral therewith and between said collars an arm 112 projects, said arm being a switch arm and adapted upon longitudinal movement of the sleeve to close a suitable switch 114 which is supported on an insulating block 116 in the bracket 12, a conductor 118 being in circuit with the bulb 20 and the switch point 114 and therefore contact of these two points 112 and 114 completes the circuit to the bulb to cause illumination.

A spring 120 between the collars 110 and the gear 108, concentric with the rotatable sleeve and of the compression type, tends to keep the sleeve pressed outwardly so that the switch is normally open and when it is desired to illuminate the dial the knob 9 secured to the outer end of the sleeve has to be pressed in to force

the sleeve in and allow the switch to close. However, if it is desired to maintain the light at all times when the set is in operation, the threaded outer sleeve 42 which projects through the supporting nut 48 and has secured thereto a control knob 124 for rotation therewith is utilized. It will be noted that when this knob 124 is turned with outer sleeve 42 the threads thereon will cause axial movement and since this sleeve presses against the collars 110 it will force the same inwardly to maintain the switch closed at all times and is therefore a locking means for the switch.

If in connecting this control head to the remote set the setting on the dial is not in accordance with the setting of the variable condensers in the set and it is desired to bring the two into correspondence, this may be done by removing the knob 9, which it will be noted from Figure 4 is the connecting means between the inner shaft 38 and the outer sleeve 40, the inner shaft 38 being connected to the tuning condenser and the outer sleeve to the dial for indication. Therefore one may be moved in relation to the other to bring the two into correct correspondence for tuning.

It is thus seen that the illumination from the bulb 20 will proceed through the transparent gear 104, through the spider and to the dial and arrow portions as desired. Rotation of the knob 7 will cause a variation in volume control at the set through a rotatable flexible drive 80; rotation of the knob 62 below the outer knob 7 will cause rotation of the tone control member 72; rotation of the knob 9 will cause a variation of tuning at the set through remote flexible drive 30 and also a rotation of the indicating arrow on the rotatable member 100 through suitable gearing; while axial movement of the knob 9 and sleeve 40 will cause a switch to the light 20, said switch being capable of being rotated in its closed position by rotating the knob 124.

It should further be pointed out that by removing the screws 52 the control means supported upon plate 50 may be moved to any desired position by threading them into suitable openings such as 126 shown at different positions on the periphery of the bracket 12.

As shown in Figure 1, the knobs are directly opposite each other but when it is necessary to place the bracket on different types of mountings, such as are necessary to fit into instrument panels in the various cars, it is often desirable to place them at such position as shown in Figures 6 and 7 and with my construction it is possible to do this without changing anything but the outer casing or face plate as the case may be. These two Figures 6 and 7 show that it is possible to move the control knob 128, corresponding to knob 7, anywhere around the periphery of the bracket 60 to give the desired location and to fit in the different panels by merely supporting it at a different position on the periphery of the bracket 12. The dial itself is then rotated to preserve symmetry inasmuch as the center line has been changed 65 and of course it is necessary to always have the dial in a correct angular position.

I claim:

1. In a remote control, a housing, parallel shafts supported in the housing, gears interconnecting the shafts whereby rotation of one causes the other to rotate, a positionally adjustable member secured to the housing and a third shaft parallel to the first two supported by the member.

2. In a remote control, a pear shaped unit,

means for rotatably supporting two spaced parallel shafts in the unit, means to drive one shaft from the other, detachable and adjustable means secured to the unit and a third rotatable and parallel shaft supported thereby, whereby the shafts all cooperate to provide a coordinating remote control.

3. In a remote control, a unit, spaced rotatable shafts supported in the unit, means for driving one shaft from the other, detachable and adjustable means secured to the unit, and a third shaft supported by the last named means whereby the position of the third shaft may be varied with respect to the other two as the installation requires.

4. In a remote radio control, a unit, a rotatable shaft supported within the unit, a dial carried thereby, a second spaced rotatable shaft carried by the unit, said second shaft being slightly axially movable, peripheral extensions on this last named shaft, a switch, a movable switch member engageable by the extensions and operable by axial movement of the shaft to operate the switch, driving means interconnecting the two shafts whereby rotational movement of the second shaft will rotate the dial and axial movement of the same the switch, axial locking means mounted

on the second shaft to maintain it in inward position to keep the switch closed and illuminating means in the unit behind the dial controlled by the switch, said means comprising a sleeve mounted upon the second shaft and means to cause said sleeve to move axially upon rotation of the sleeve, said axial movement causing the locking.

5. In a remote control, a unit, an indicating dial carried by the unit, a tuning shaft also carried by the unit, means for driving the dial from the shaft, switching means carried by the unit, means for operating the switching means from axial movement of the shaft, illuminating means in the unit controlled by the switch, separable and adjustable means secured to the unit and volume and tone control means carried by this last named means.

6. In a remote control, a unit, spaced rotatable shafts supported by the unit, means for driving one shaft from the other, adjustable means secured to the unit, and a third shaft supported by the last-named means whereby the position of the third shaft may be varied with respect to the other two as the installation requires.
